UNITED STATES PATENT OFFICE.

WILLIAM E. SIMPSON, OF DETROIT, MICHIGAN, ASSIGNOR TO PALMER-BEE COMPANY, OF DETROIT, MICHIGAN, A CORPORATION OF MICHIGAN.

AUTOMATIC STOP MECHANISM FOR POWER HOISTS.

Application filed December 19, 1919. Serial No. 345,976.

To all whom it may concern:

Be it known that I, WILLIAM E. SIMPSON, a subject of the King of Great Britain and Ireland, residing at Detroit, in the county of Wayne and State of Michigan, have invented certain new and useful Improvements in Automatic Stop Mechanism for Power Hoists, of which the following is a specification, reference being had therein to the accompanying drawings.

The invention relates to power operated hoists and consists in the novel construction of stop mechanism by which the movement of the hoist is automatically arrested before reaching the hoisting limit. The invention further consists in the construction of a stop mechanism unit which is attachable to a hoist unit unprovided with such mechanism, and further in various features of construction as hereinafter set forth.

In the drawings:

Figure 1 is a central longitudinal section through a manual operable hoist;

Figure 2 is a similar view through the construction converted into a power hoist and provided with my improved stop mechanism.

Figures 3, 4 and 5 are sectional views taken on the lines 3—3, 4—4 and 5—5, respectively, of Fig. 2.

As shown in Figure 1, A is a housing for enclosing the hoist mechanism; B is a swivelled hook forming a support for said housing; C is a chain wheel for manual operation; D is a shaft on which said chain wheel is mounted extending axially through the housing A. E is a driven chain wheel sleeved upon the shaft D and provided with load-supporting roller bearings F. G is a pinion on the shaft D in mesh with planetary pinions H engaging an annular internal gear rack I upon the housing, and J are journal pins for said planetary gear wheels which are carried by a head K mounted on a sleeve extension L of the driven wheel E.

The construction above described is designed for manual operation, but is adapted for attachment of a power unit thereto. To this end the housing A is provided with a detachable end cover M which, when removed, permits of registering with said housing an auxiliary housing N containing a motor unit O and a step-down transmis-

sion gearing P for coupling the same with the shaft D. When so equipped, the hoist can be power operated but there is danger that a careless operator might run the motor beyond the hoisting limit with disastrous results.

To apply my stop mechanism to the construction, the peripheral portion C' of the operating wheel C is removed by disengagement of the attachment screws C². An auxiliary housing Q may then be attached to the end of the housing A, said auxiliary housing enclosing the stop mechanism.

This mechanism comprises a rotary shaft R which is screw-threaded for engagement with a pinion S, said pinion being in mesh with a long tooth gear wheel T mounted on a shaft U. The pinion S has a limited freedom for longitudinal movement on the shaft R when the latter is revolved, but at opposite ends are arranged stops V and V' which

prevent further movement and cause the locking of the pinion rotatively to the shaft. The shaft R is revolved from the shaft D by means of the gears D' and R' upon the shafts D and R respectively, the gears D' being substituted for the washer D² in the manually operated hoist. The gear wheel T has its teeth of sufficient length to remain in mesh with the pinion during its movement along the shaft R, but when said pinion is

locked rotatively to the shaft, further rotation thereof will cause the transmission of rotary movement to the gear wheel T. The gear wheel T is yieldably held in a neutral position by resilient means, such as the spiral spring W, which as shown is arranged within a recess in the gear and has one end connected to the gear and its opposite end connected to a stationary stop X, so that whenever the pinion S is free to revolve, the gear wheel will be returned to its neutral position.

Secured to the shaft U is a switch arm U' forming an element of a circuit closer and rheostat of any suitable construction for controlling the motor O, and U² is an operating arm attached to the shaft U and adapted to be manually actuated to control the operation of the motor.

Within the housing Q are also arranged fuses Y and other accessories of the electric control and said housing is preferably formed in sections hinged to each other at Q' and normally locked by a bolt Q². The

arrangement is such that by unfastening the bolt Q^2 the housing Q may be opened to provide access to the switch.

In changing the hoist from a manually operable construction to the power actuated and automatically stopped construction the operator first removes the cover M and places in position the housing N , as has been previously described. He also disengages the peripheral portion C' of the operating wheel C , which permits of engaging the housing Q with the stop mechanism arranged therein. When thus changed, the hoist is power driven and is both manually and automatically controlled.

What I claim as my invention is:

1. A stop mechanism for hoists, comprising a controlling switch, mechanism for throwing said switch including a driven gear wheel, a driving gear wheel in mesh with and having its axis parallel to that of said driven gear wheel said driving gear wheel being longitudinally slideable in mesh with said driven gear wheel, a screw threaded shaft on which said driving gear wheel is mounted for causing the longitudinal movement thereof upon the rotation of said shaft, and a stop for limiting the longitudinal movement of said driving gear wheel upon said shaft to cause the rotation of said driving gear wheel with the shaft and the rotation of said driven gear wheel and the actuation of said switch.

2. A stop mechanism for hoists, comprising a controlling switch, mechanism for operating said switch including a shaft connected to said switch, a driven gear wheel connected to said shaft, a driving gear wheel longitudinally slideable in mesh with said driven gear wheel, a screw threaded shaft having its axis parallel to that of said first-mentioned shaft and on which said driving gear wheel is mounted, said screw threaded shaft being adapted to cause the longitudinal travel of said driving gear wheel upon rota-

tion of said screw threaded shaft, a stop ar- 50
resting longitudinal travel of said driving gear wheel upon said screw threaded shaft to cause the rotary movement of said driving gear wheel, and the rotary movement 55
of said driven gear wheel, and mechanism driven from the hoist for rotating said screw threaded shaft.

3. A stop mechanism for hoists comprising an electric switch, a resilient yieldable connection for throwing said switch, a long-toothed gear wheel to which one end of said resilient yieldable connection is attached, a pinion in mesh with and having its axis parallel to that of said long-toothed gear wheel, a screw-threaded shaft on which said pinion is mounted, the rotation of said shaft causing the longitudinal travel of said pinion thereon while in mesh with said long-toothed gear, a stop for limiting the longitudinal movement of said pinion to cause 70
the rotation of the same with said shaft, and mechanism driven from the hoist for actuating said screw-threaded shaft.

4. A stop mechanism for hoists, comprising an electric switch, a resilient connection 75
for normally maintaining said switch in neutral position, a long toothed gear wheel within which said resilient connection extends and to which one end of said resilient connection is attached, a pinion in mesh with 80
said long-toothed gear wheel, a screw-threaded shaft on which said pinion is mounted, the rotation of said shaft causing the longitudinal travel of said pinion thereon, while in mesh with said long-toothed gear wheel, a stop upon said screw-threaded shaft for limiting the longitudinal movement of said pinion to cause the rotation of the same with said shaft, and mechanism 85
driven from the hoist for actuating said 90
screw-threaded shaft.

In testimony whereof I affix my signature.

WILLIAM E. SIMPSON.
